UNITED STATES PATENT OFFICE.

EDWARD BRUNHOFF, OF WYOMING, OHIO, ASSIGNOR TO THE BRUNHOFF MANUFACTURING COMPANY, OF CINCINNATI, OHIO, A CORPORATION OF OHIO.

ROTATABLE DISPLAY STAND.

Application filed October 1, 1927. Serial No. 233,413.

My invention relates to improvements in revoluble display stand or rack. One of its objects is to provide an improved display rack adapted to support and display four-in-hand neck ties and similar articles. Another object is to provide a display stand in which the supporting racks are relatively adjustable and are collectively rotatable upon their supporting stand. Another object is to provide for limiting the relative movement of the rack members so that while they may be parted to display the goods suspended thereon they are not permitted to concentrate the collective weight of the rack members and articles suspended thereon upon one side of the stand so as to render the stand liable to be upset by a concentration of weight upon one side of the stand. Another object is to provide an improved assembly of stand, rotatable member and detachable rack members adapted to be conveniently produced, packed for shipment, and assembled for the purposes intended. Another object is to provide an improved assembly of rotating member and rack members detachably and adjustably interlocked therewith. My invention also comprises certain details of form and arrangement and combination of components, all of which will be fully set forth in the description of the accompanying drawings, in which:

Fig. 1 is a side elevation partly in central vertical section, of a display stand or rack embodying my invention.

Fig. 2 is a plan view of the stand shown in Fig. 1.

Fig. 3 is a plan view of one of the rack members detached.

Fig. 4 is an enlarged detail illustrating the manner of limiting the adjustment of the rack members relative to the rotatable member.

The accompanying drawings illustrate one embodiment of my invention in which 15 represents a stand or stationary member comprising a base 16, and a standard 17 projecting upwardly therefrom and provided with a shoulder 18. The base 16 is provided with soft rubber pads 19 where the base is designed to rest upon a counter or show-case, so as not to be liable to break or mar the object upon which the base 16 rests.

A rotatable member comprises a metal tube 20 to the lower end of which is rigidly attached a downwardly cupped flange 21, and

to the upper end of which is rigidly attached a downwardly cupped flange 22 having an annular apron 44 extending downwardly therefrom. The lower end of the tube 20 rests upon the shoulder 18 of the standard 17, 60 and the internal diameter of the tube is slightly greater than the external diameter of the standard 17 above said shoulder 18, so that the tube 20 and flanges 21 and 22 rotate freely upon the standard 17. 65

The flange 21 is provided near its periphery with a series of perforations 24, and the flange 22 is provided near its periphery with a series of perforations 25. The perforations 24 and 25 are arranged concentrically 70 about the tube 20, and are uniformly spaced apart. I preferably provide twenty-four perforations 24, through the flange 21, and a like number of perforations 25 through the flange 22. 75

A series of rack members 26 are provided by bending sections of wire to substantially the outline shown in Fig. 3. The lower ends of the rack members are curved or hooked at 27 and in assembling the rack members upon the rotatable member, are first engaged through the perforations 24, after which the upper end sections 28 are sprung upwardly away from the ends 27 and flange 21 until the end 28 clears the top of the flange 22 and 80 permit the end 28 to be introduced from above into one of the perforations 25 in the flange 22 vertically above the perforation 24 engaged by the lower end 27 of said rack member. The ends of the rack members are 85 held resiliently in position relative to the flanges 21 and 22, and each rack member has a limited movement pivotally relative to the flanges 21 and 22, with the center of the perforations 24 and 25, which it engages as 90 a vertical axis of adjustment. Each rack member has a horizontal section 30 adjacent to its end 28, which rests upon the upper face of the flange 22, and a short vertical section 31 adjacent to the horizontal section 30, 100 which extends downwardly outside of the cupped rim of the flange 22, and describes an arc about the end 28, which arc is limited by contact of the section 31 with the rim of the flange 22 to limit the pivotal adjustment of 105 the rack members relative to the rotatable member.

Each rack member is preferably subdivided along its horizontal section 32 into a series of channels or spaces 33 by means of in- 110

terposed bends or humps 34. Each space 33 is designed to receive one of the articles to be displayed. The upward loop 35 at the outer limit of each horizontal section serves to confine and prevent the articles on display being drawn endwise from the rack members. The lower curved end 27 is locked in position in the flange 21 whenever the upper end 28 of a rack member is seated in a perforation 25, 10 and it is only after the end 28 has been detached and moved radially away from the flange 22, that the lower end 27 reaches a position to be freed from its engagement with the flange 21. A price tag holder 42 is detachably mounted upon the upper end of the pedestal 17.

The diagonal sections 36 of the rack members serve to brace and support the outer ends of the horizontal sections 32, and the weight 20 of the articles carried thereby, thus providing in the rack members light weight combined with rigidity and strength to carry the loads required. By providing six spaces 33 to each rack member the twenty-four rack 25 members are adapted to support and display a gross of articles, and in a compact space, while readily permitting the rack members to be parted as indicated in Fig. 4, so as to permit any one of the articles to be exposed to view and 30 to light from any source or direction. By limiting the extent to which any one rack member may be moved pivotally relative to the rotatable member, the weight of the rack

members and weight of the goods carried thereby are not permitted to be sufficiently 35 concentrated upon one side of the supporting standard 17 so as to cause the stand to be thereby upset.

The apparatus herein shown and described is capable of considerable modification within 40 the scope of the claim without departing from the spirit of my invention.

What I claim is:

A display stand comprising a base member having a pedestal extending upwardly therefrom, a rotatable member journaled upon said pedestal above said base member, and provided with an upper perforated flange and a lower perforated flange, a series of rods bent to form rack members each having a substantially horizontal supporting arm and an upwardly and outwardly inclined brace arm, a hook at the lower inner end of each of said brace arms to engage and interlock with a perforation in said lower flange, a hook at the inner end of each of said supporting arms to resiliently engage from above with a perforation in said upper flange to pivotally support said rack members upon and relative to said 55 rotary member, and means to limit the pivotal movement of said respective rack members relative to said rotary member.

In testimony whereof I have affixed my signature.

EDWARD BRUNHOFF
